UNITED STATES PATENT OFFICE.

JAMES C. POTTER AND JOHN JOHNSTON, OF PAWTUCKET, RHODE ISLAND, ASSIGNORS TO THE POTTER AND JOHNSTON MACHINE COMPANY, OF PAWTUCKET, RHODE ISLAND, A CORPORATION OF RHODE ISLAND.

FRICTION-CLUTCH.

SPECIFICATION forming part of Letters Patent No. 730,962, dated June 16, 1903.

Application filed October 5, 1900. Serial No. 32,072. (No model.)

To all whom it may concern:

Be it known that we, JAMES C. POTTER, a citizen of the United States, and JOHN JOHNSTON, a subject of the King of Great Britain, both residing at Pawtucket, in the county of Providence and State of Rhode Island, have invented a new and useful Improvement in Friction-Clutches, of which the following is a specification.

10 In the transmission of power shafts supported in hangers are connected together end to end by couplings secured to the adjacent ends of the shafting, and for the purpose of transmitting power from the line of shafting to machines pulleys are secured to the shafts, which pulleys in many instances are loose on the shaft and require to be secured by 15 clutches.

The invention has reference to an improvement 20 in the construction of friction-clutches whereby shafts may be connected at their ends or loose pulleys connected to the shaft and readily disconnected; and it consists in the peculiar and novel construction whereby 25 the clamping-arms are operated by screw-spindles through rack-bars engaging with pinions on the screw-spindles and connected to a shipper-sleeve, as will be more fully set forth hereinafter.

30 The object of the invention is to more securely couple the ends of shafts together or loose pulleys with the shaft and to permit the uncoupling of the shafts or pulleys without the use of tools.

35 Figure 1 is a side view of our improved friction-clutch. Fig. 2 is a transverse sectional view of the same. Fig. 3 is a longitudinal sectional view of part of the clutch on a radial line through the center of one of the 40 three clamping-arms. Fig. 4 is a sectional view showing the rack-bars in connection with the pinion on the screw operating one of the clamping-arms. Fig. 5 is a perspective view of a thrust-block preferably used in 45 coupling two ends of shafts together. Fig. 6 is a longitudinal sectional view of a form of friction-clutch containing our invention, showing modifications in the details of construction in connection with a loose pulley.

Similar marks of reference indicate corresponding parts in all the figures.

In the drawings, a and a' indicate shafts used for the transmission of power, a^2 a circular disk having the hub a^3 formed integral therewith, and a^4 radial ways in the disk a^2 , in which the clamping-arms a^5 are operated by the screw-spindles a^6 . The parts of the clamping-arm a^5 in screw-thread connection with the screw-spindle a^6 fit the rear part of the way a^4 beyond the ribs a^7 , which part is of U-shaped cross-section with a sliding fit.

As the traverse of the clamping-arms in friction-clutches is limited to the mere clamping and unclamping, parts of the ribs a^7 may be omitted to facilitate the insertion of the enlarged part of the clamping-arms from the front of the disk a^2 .

In the preferred construction, as shown in Figs. 2, 3, and 4, the clamping-arms a^5 are provided with the segmental brackets a^8 , in the ends of which a suitable bolster a^9 is secured. The portion of the arm a^5 extending into the ways a^4 is divided into an upper and a lower part, between which the pinion a^{10} is secured to the screw-spindle a^6 . The screw on the upper part of the screw-spindle is of larger diameter than the screw on the lower part of the spindle, but of the same pitch. The disk a^2 is provided with the annular ring a^{11} , which is secured when the clamping-arms a^5 , with the screw-spindles a^6 , are screwed down so that the end bearing a^{12} of the screw-spindles is below the inner surface of the annular ring a^{11} . They are now turned to bring the shoulder of the bearing a^{12} on a line with the inner surface of the annular ring a^{11} . The screw-plugs a^{13} are screwed in the annular ring, so as to bear on the shoulders, and then secured against rotation by the screw a^{14} . The rack-bars b engage with the pinion a^{10} and slide in the ways b' . The rack-bars are connected, by means of the pins b^2 , with the shipper-sleeve b^3 , which slides on the outer surface of the hub a^3 and is operated by a shipper-lever.

The operating devices forming the clutch mechanism are shown in Fig. 1 connected to

the shaft a' . The thrust-block c , preferably of hardened steel, is placed between the ends of the adjacent shafts a and a' with the screw-spindles a^6 bearing on the three flattened sides 5 of the thrust-block. On the end of the shaft a the pulley d is secured in the usual manner by means of a groove and spline or a set-screw. The inner surface of the rim d' extends over the brackets a^8 and receives the radial thrust 10 of the three clamping-arms a^5 , to which the segmental brackets a^9 are secured, and thereby connects the clutch mechanism with the pulley d and the shaft a' with the shaft a . d^2 is a panel closing an opening in the web of 15 the pulley d , by which access may be gained to the brackets a^8 for adjustment or repair.

In the modified form shown in Fig. 6 the clutch-operating mechanism is simplified and the cost materially reduced, while the operations and the operative elements are the same. In Fig. 6 the clutch-operating mechanism is shown in connection with a loose pulley, both on one length of shafting; but the pulley may be secured to the end of one 20 shaft and the clutch to the adjacent end of another shaft similarly to the construction shown in Fig. 4. The screw-spindle a^6 bears directly on the shaft and has a screw-thread of uniform diameter. The pinion a^{10} is near 25 the end of the screw-spindle a^6 , and the clamping-arm a^5 is formed integral with the bracket a^8 , which bears on the inner surface of the loose pulley. The diameter of the hub a^3 is much less than it is in the preferred 30 construction.

Having thus described our invention, we claim as new and desire to secure by Letters Patent—

1. In a friction-clutch, the combination of 40 a shaft, a clutch member thereon, clamping-arms to engage such member, a radially-disposed screw for each clamping-arm, bearings that engage the screw at opposite ends by 45 which it is supported against endwise movement, and means for revolving said screw,

substantially as and for the purpose described.

2. In a friction-clutch, the combination of a shaft, a clutch member thereon, clamping-arms to engage such member, a radially-disposed screw for each clamping-arm, bearings that engage the screw at opposite ends by which it is supported against endwise movement, and a rack and pinion for each screw, the pinion being mounted on the screw in a 55 space between two parts of the arm, substantially as and for the purpose described.

3. In a friction-clutch, the combination of alining shafts, a clutch member on one of the shafts, a clutch member on the other, comprising radially-disposed operating-screws, and a thrust-block for the screws placed between the ends of the shafts, substantially as 60 and for the purpose described.

4. In a friction-clutch, the combination of 65 alining shafts, a clutch member on one of the shafts, clamping-arms carried by the other shaft, a radially-disposed operating-screw for each clamping-arm, and a thrust-block for the screws placed between the ends of the 70 shafts, substantially as and for the purpose described.

5. In a friction-clutch, the combination of a shaft, a pulley thereon, clamping-arms to engage the pulley, a radially-disposed screw 75 engaging each arm, a rack and pinion for each screw, and means for supporting the screws against endwise movement comprising a centrally-placed thrust-block, against which the ends of the screws abut, substantially as and for the purpose described. 80

In testimony whereof we have signed our names to this specification in the presence of two subscribing witnesses.

JAMES C. POTTER.
JOHN JOHNSTON.
